UNITED STATES PATENT OFFICE.

FREDERICK H. CUMMER, OF LOS ANGELES, CALIFORNIA.

DRIER FOR ROAD MATERIALS.

Application filed November 19, 1925. Serial No. 70,103.

This invention relates to driers for road materials, such as for crushed rock, stone or like material to be used in asphalt or other pavements.

5 The object of the invention is to provide a drier in which the heat is developed and applied most efficiently to the road material and with the least possible deterioration of the heating drum which, with the furnace 10 and heating apparatus, is arranged for protection of all parts usually exposed to the flames in a manner to avoid burning out and other harmful results.

In the drawings, which represent one suitable embodiment of the invention, Fig. 1 is a side elevation; Fig. 2 is a detail longitudinal sectional elevation on the line 2—2, Fig. 3; Fig. 3 is a cross section on the line 3—3, Fig. 1; and Fig. 4 is a sectional plan view 20 on the line 4—4, Fig. 1; Fig. 5 is a detail sectional plan view on the line 5—5, Fig. 2.

For the most part the apparatus requires no detailed description, because it is generally like the drier of my prior patent for asphalt mixing apparatus, granted February 25 3, 1920, No. 1,329,506. As illustrated, it comprises a suitable frame 1 mounted on wheels 2 and which frame may be jacked up or otherwise supported temporarily in the 30 proper position at the place of duty. On said frame is a stationary jacket 3 within which rotates a hollow drum 4 provided with tires 5 at its opposite ends mounted on rollers in the frame. The drum is inclined 35 slightly from left to right in Fig. 1, the crushed rock or other material being delivered to its left end and passing through the drum from which it is discharged at its opposite open end to an encased conveyor 40 6 which elevates it to storage bins, not shown, such as those shown in my prior patent referred to. As the material passes through the drum it is heated, both for the purpose of removing moisture and for its 45 more ready incorporation with asphalt or other material of the road mixture.

Below the drum the stationary jacket supports a furnace jacket 10 having one or more firing or inspection doors 11, a grate 12 and 50 side and end walls lined with refractory material, as at 13. While the furnace may be fired from the side with coal, wood or

other fuel in emergencies, it is here shown as equipped for use with gas or liquid fuel, such as fuel oil, in which case spaced fire 55 brick 14 are laid upon the grate. At its feeding end the drum 4 is exposed to the outer air, to carry both the tire 5 and its end driving gear 15, the joint between the exposed end of the drum and the stationary 60 casing 3 being suitably sealed, as at 16, by a metal plate or in any other suitable manner. At its opposite end, the drum also extends beyond the stationary jacket 3, its 65 outer surface being thereby exposed to the protective effect of the cooler outer atmosphere and not being subjected to the fire or to direct flame applied thereto, and on its exposed portion, marked 16, is located the 70 other tire 5. The furnace jacket 10 extends 75 toward the discharge end of the drum as far as the end of the stationary jacket 3, whatever be its length. At the feeding end of the drum, the furnace is extended to provide a mixing and combustion chamber 17 at the outer end of which are located one or 80 more suitable burners 18 for the gaseous or liquid fuel. This furnace extension is also lined with refractory material, and where it joins the main expansion chamber 19 in 85 furnace 10 its walls are flared, as at 20, to provide fairly smooth wall surfaces which will not unduly impede travel of the flame or the heated products of combustion. The far end of the furnace chamber, with its 90 lined wall 21, serves as a baffle for the flames or heated products of combustion, and said wall and the grate bricks 14 produce a reverberatory effect with a more uniform application of the heat to the drum and to the 95 material within the same.

The vaporized liquid fuel, if such is used, together with the air to be mixed therewith, travel back through the mixing and combustion chamber 17, and are permitted to thoroughly mix therein, combustion beginning in said chamber and being completed in the expansion chamber 19 where the gases are permitted to completely expand. The flames are allowed to develop quietly and to mature 100 before they actually contact with the wall of the drum. However, to protect the drum its outer surface, within the furnace chamber 19, may carry a series of protecting or

baffling members, such as cast metal plates 22, shown as rectangular, and provided at the four corners with legs 23 to space them from the wall of the drum, to which they are secured by center bolts 24. Gaps are left between adjacent plates, so that the hot gases can readily flow to and through a series of openings in the drum wall and communicating within the drum with the several 10 hooded inlets 25 of the same form shown in my prior patent referred to.

With this arrangement the hot gases are developed fully and flow directly to the inside of the drum and thence to the chimney 15 26 at the feeding end, so that the most intense heat is applied to the material at the feed end of the machine. In other words, by the time the material has progressed to about the end of the zone of the 20 furnace chamber 19 it has been fully dried and heated. However, to not only maintain its dry condition and the temperature to which it has been raised and indeed, to additionally heat it, if necessary, means is also provided for applying heat and hot 25 gases to the discharge end of the drum. For this purpose the discharge end of the drum, as shown in Fig. 4, enters a chamber within a stationary end jacket 27 also lined with refractory material, the joint between said jacket and drum being again sealed by a metal plate, as at 28. At the bottom of the chamber therein is an opening communicating with a chute 28, Fig. 1, leading 30 to the elevator 6. In the end of the jacket and axially co-aligned with the drum is a fire inlet comprising a jacket 29 lined with refractory material 30, the inner surface of which flares outwardly toward the drum, 35 as shown in Fig. 4. At the outer end of the mixing and combustion chamber therein is located the burner 31. With this arrangement the flared opening through the fire inlet permits the mixture of air and 40 combustible material to become thoroughly mixed and the flames produced by combustion thereof to develop in the chamber of the jacket 27, from which the gases flow directly into the fully exposed open end of 45 the rotating drum. Here the gases are applied directly to the inside of the drum which is protected by the material being carried along with it toward the outlet, so that direct application of the flame to the 50 metal of the drum is not so serious, in addition to which the outer surface of the drum is exposed to the open air and is thereby protected.

This construction largely reduces the cost 55 in time, labor and material for replacing drums where the intense heat has either burned clear through the material or burned out its carbon to such an extent that the metal has lost its mechanical strength and is either broken or distorted. It there-

fore not only decreases the cost for repairs, but enables the apparatus to be kept in commission for a longer time without being shut down with consequent loss of valuable time and increase in overhead charges.

70

What I claim is:

1. A drier for road materials, comprising a frame, a rotatable drying drum through which the material is fed and provided with hot gas inlets, a stationary jacket 75 around said drum, a furnace jacket below said stationary jacket and having an expansion chamber open to the space therein and communicating with said inlets, said furnace jacket having an extension at one end and provided with a combustion chamber leading into said expansion chamber and into the outer end of which burners may extend.

2. A drier for road materials, comprising a frame, a rotatable drying drum through which the material is fed and provided with hot gas inlets, a stationary jacket around said drum, a furnace jacket below said stationary jacket and having an 80 expansion chamber open to the space therein and communicating with said inlets, said furnace jacket having an extension at one 85 end and provided with a combustion chamber leading into and having its walls diverging toward said expansion chamber and into the outer end of which burners may extend.

3. A drier for road materials, comprising a frame, a rotatable drying drum thereon, a stationary jacket surrounding the discharge end of said drum having an inner 100 expansion chamber in open communication with the open end of the drum, and an extension for said stationary jacket having a 105 combustion chamber therein communicating with the expansion chamber in said stationary casing.

4. A drier for road materials, comprising a frame, a rotatable drying drum thereon 110 having an open discharge end, and a stationary furnace jacket at the discharge end of said drum and provided with combustion and expansion chambers and a burner receiving opening coaxially aligned with 115 the drum.

5. A drier for road materials, comprising a frame, a stationary furnace jacket thereon, a rotatable drying drum extending through said furnace jacket and having a 120 material portion of its length at the discharge end located outside of said jacket and exposed to the outer air, and a stationary furnace jacket located at the discharge end of said drum and into which the 125 latter extends.

6. A drier for road materials, comprising a frame, a stationary jacket, a rotatable drying drum extending through said jacket and projecting beyond the same at both 130

ends, and protecting means carried on the side of said drum within said jacket, and a stationary furnace jacket at the discharge end of said drum and into which the same extends. 10

7. A drier for road materials, comprising a frame, a stationary jacket, a rotatable drying drum extending through said jacket and projecting beyond the same at both ends, protecting means carried on the out-

In testimony whereof I hereby affix my signature.

FREDERICK H. CUMMER.
